UNITED STATES PATENT OFFICE.

AARON P. GOULD, OF CANTON, OHIO.

HEAD-REST.

SPECIFICATION forming part of Letters Patent No. 634,083, dated October 3, 1899.

Application filed July 24, 1899. Serial No. 724,958. (No model.)

To all whom it may concern:

Be it known that I, AARON P. GOULD, a citizen of the United States, residing at Canton, in the county of Stark and State of Ohio, have 5 invented certain new and useful Improvements in Head-Rests; and I do hereby declare the following to be a full, clear, and exact description of the invention, such as will enable others skilled in the art to which it app- 10 pertains to make and use the same.

This invention relates to head-rests for dental and other purposes; and the object is to simplify the construction, increase the convenience and utility, and provide a device of 15 this character which is capable of a practically universal range of adjustment.

To this end the invention consists in the construction, combination, and arrangement of the several elements of the device, as will 20 be hereinafter more fully described, and particularly pointed out in the claims.

In the accompanying drawings the same reference characters indicate the same parts of the invention.

25 Figure 1 is a perspective view of my improved head-rest. Fig. 2 is a vertical section, partly in elevation, of the same. Fig. 3 is an enlarged detail view of the clamping- rods and screw. Fig. 4 is a detail perspective 30 view of one of the socket-heads, and Fig. 5 is a similar view of the socket-cap. Fig. 6 is a side elevation of one of the cap-screws. Fig. 7 is a vertical section of the sliding carriage. Fig. 8 is an enlarged perspective view of the 35 pad-supporting frame and a portion of the horizontal arm of the tubular bracket. Fig. 9 is a detail section of the same. Fig. 10 is a plan view partly in section to show the manner of adjusting the pad-plates inde- 40 pendently of the supporting-arms. Fig. 11 is a similar view to show the manner of adjusting the supporting-arms. Fig. 12 is a perspective view of the pad-supporting frame 45 socket-head. Fig. 13 is a detail perspective view of one of the mutilated gears to which the inner end of the connecting-rods is pivoted. Fig. 14 is a similar view of one of the pad-supporting arms, and Fig. 15 is a similar 50 view of the outer end of one of the arms with the connecting-rod extending through it. Fig. 16 is a side elevation, partly in section, of a rigid form of pad-supporting frame.

In the drawings, 1 denotes the dovetail rail, which is fixed in a vertical position to the back of the chair, (not shown,) and 2 denotes 55 the carriage formed with a corresponding groove 2' to encompass the rail, with which it has a longitudinal sliding engagement.

2² denotes a spherical knob or ball formed integral with the sliding carriage and provided with a threaded orifice 2³, which also extends through the carriage to receive the hand-screw 3, the inner end of which impinges or abuts against the rail to adjustably 60 secure the carriage in place. 65

4 denotes a right-angular bracket, the lower end of which terminates in a socket 4', to which the cap 4² is removably secured by the cap-screws 4³, the whole encompassing the knob 2² and forming a "ball-and-socket" joint between the carriage and the bracket. The horizontal arm of this tubular bracket also terminates in a corresponding socket 4⁴, and its cap 4⁵ is also removably secured thereto by the cap-screws 4⁶, the whole encompassing 70 the spherical knob 5, formed on the lower end of the shank 5' of the pad-supporting frame, so as to form a ball-and-socket connection between the tubular bracket and the pad-supporting frame. 75

6^a and 6^b denote clamping- rods loosely mounted in the tubular arms of the angular bracket, their outer ends abutting against the knobs 2² and 5, respectively, and their meeting ends form an angle of forty-five degrees, 80 the apex of which is cut off to form a plane bearing-face lying at a right angle to the plane of the dividing-line between the parallel faces of the meeting ends of said clamping-rods.

7^a designates an internally-threaded boss 90 formed on the apex of the tubular bracket to receive the hand-screw 8, the free end of which abuts against the meeting ends of the rods 6^a 6^b to simultaneously force them outwardly and clamp or bind the knobs 2² and 5 in their respective sockets. The upper end of the shank 5' terminates in a socket-head 5², to which the cap-plate 5³ is removably secured by the cap-screws 5⁴, which latter extend through the orifices 5⁵ 5⁵ and enter 95 a follower-plate 6, so as to clamp the plate, socket, and cap rigidly together. This plate 6 is provided with parallel stud-pins 6' 6', on which are fulcrumed the tubular curved arms 100

7 7', the hubs of which are formed with intermeshing teeth 7² 7², so that the adjustment of said arms is simultaneous, the adjustment of one being imparted to the other.

5 8' 8' denote arm-plates, each of which is formed with the parallel flanges 8² 8², between which the outer ends of the arms 7 7' are pivoted on the stud-pins or rivets 8³.

9 9' denote connecting-rods, having their 10 outer ends pivoted on the stud-pins 9² in the outer ends of the flanges 8² and their inner ends on the wrist-pins 10² 10², concentrically fixed on the intermeshing mutilated gears 10 10', mounted on the stud-pins 6 6' in the head 15 5² and parallel with the hub portions of the arms 7 7.

11 denotes a pressure-plate resting on the intermeshing toothed portions of the mutilated gears 10 10', and 12 denotes a thumb-screw 20 mounted in the boss 5⁵ of the cap-plate 5³, with its inner end abutting against the pressure-plate, so that the contiguous ends of the arms 7 7' and the gears 10 10' may be rigidly clamped in any position to which they 25 may be adjusted.

13 13' denote the pad-plates, to which the pads 14 14' are fixed, and they conform in shape to the arm-plates 8 8', to which they are pivoted by the rivets 13², and are secured in 30 their adjusted positions by the thumb-screws 15 15, which pass through the segmental slots 8⁴ in the arm-plates and extend into the pad-plates.

The various adjustments of the rest are so 35 plainly illustrated in the several figures as to be readily comprehended by those skilled in the art, and consequently do not require an extended description.

Briefly stated, what may be termed the 40 "coarse" or "preliminary" adjustment is attained through the medium of the hand-screws 3 and 8 and the fine or secondary adjustment by means of the thumb-screw 12, and the final adjustment to conduce to the greater comfort of the patient's position by means of the 45 thumb-screws 15.

In Fig. 16 I have shown a rigid form of pad-supporting frame which is adjustably secured in the same manner in the horizontal arm 4⁴ 50 of the tubular bracket 4.

The accompanying drawings show my invention in the best form now known to me; but many changes in the details might be made within the skill of a good mechanic 55 without departing from the spirit of my invention as set forth in the claims at the end of this specification.

Having thus fully described my invention, what I claim as new and useful, and desire to 60 secure by Letters Patent of the United States, is—

1. The combination, in a head-rest, of a supporting-plate, oppositely-disposed crank-arms pivotedly connected to said plate, independent pads pivotedly connected to said crank-arms, means for operating the crank-arms in unison and a locking device adapted to si-

multaneously lock said arms in position, substantially as and for the purpose set forth.

2. A dental head-rest, comprising the fixed 70 support, a carriage having a sliding engagement with said support and terminating in a spherical knob, a bracket mounted on said knob, and a hand-screw extending through said bracket, knob and carriage and abutting 75 against said fixed support to clamp or fix the carriage in place, substantially as and for the purpose set forth.

3. A dental head-rest comprising a carriage 80 formed with a spherical knob and a pad-supporting frame also formed with a similar knob; in combination with a right-angular bracket encompassing said knobs, a pair of independent rods arranged at right angles and loosely mounted in said bracket with their 85 outer ends abutting against said knobs, and a clamping-screw having a threaded engagement with said bracket, and having its free end abutting against the contiguous ends of said rods, substantially as and for the purpose 90 set forth.

4. A dental head-rest, comprising a traveling carriage, a bracket mounted on said carriage, and a pad-supporting frame mounted on said bracket, a pair of rods loosely mounted 95 in said carriage at approximately right angles to each other with their inner ends in contact and with their free ends impinging on the carriage and frame respectively, and a clamping-screw having a threaded engagement with said 100 bracket in the plane of the angle bisecting the meeting ends of said rods, substantially as and for the purpose set forth.

5. In a dental head-rest, a pad-supporting frame, comprising a shank terminating in a 105 head, a pair of arms having their hubs formed with intermeshing gears pivoted in said head and means for simultaneously locking said intermeshing gear-hubs in position, substantially as and for the purpose set forth.

6. In a dental head-rest, a pad-supporting frame, comprising a shank formed with a head, a pair of arms having their contiguous ends pivoted in said head, and a clamping-screw carried by said head and adapted to simultaneously engage the contiguous pivoted ends of said arms, substantially as and for the purpose 115 set forth.

7. In a dental head-rest, a pad-supporting frame, comprising a shank formed with a head, 120 a pair of arms having their contiguous ends pivotally mounted in said head, a pair of counterpart pads or cushions pivoted on said arms and means for simultaneously adjusting said pads independently of the position of said 125 arms, substantially as and for the purpose set forth.

8. In a dental head-rest, a pad-supporting frame, comprising a shank formed with a head, 130 a pair of coacting arms pivoted in said head, arm-plates pivoted to the free ends of said arms, and the pad-plates pivotedly secured to said arm-plates, substantially as and for the purpose set forth.

9. In a dental head-rest, a pad-supporting frame, comprising a shank formed with a head, a pair of coacting arms fulcrumed in said head, and a pair of intermeshing mutilated gears mounted in said head and provided with concentric wrist-pins; in combination with a pair of independent arm-plates pivoted on the free ends of said arms, and a pair of rods connecting said wrist-pins and arm-plates, substantially as and for the purpose set forth.

10. In a dental head-rest, a pad-supporting frame, comprising the head, the arms pivoted

in the head, the arm-plates pivoted in the free ends of said arms, the pad-plates pivoted to said arm-plates, and means for independently adjusting said pad-plates in their own planes, substantially as and for the purpose set forth. 15

In testimony whereof I have hereunto set my hand in the presence of two subscribing witnesses.
